G. D. McINTOSH

NEWSPAPER HOLDER

Filed Dec. 18, 1924

INVENTOR.

George D. McIntosh
BY Frank G. Lurman

ATTORNEY.

UNITED STATES PATENT OFFICE.

GEORGE D. MCINTOSH, OF BAY CITY, MICHIGAN, ASSIGNOR OF ONE-HALF TO HARRISON W. GARLAND, OF BAY CITY, MICHIGAN.

NEWSPAPER HOLDER.

Application filed December 18, 1924. Serial No. 756,682.

To all whom it may concern:

Be it known that I, GEORGE D. MCINTOSH, a citizen of the United States of America, and a resident of Bay City, in the county of Bay and State of Michigan, have invented new and useful Improvements in Newspaper Holders, of which the following is a specification.

This invention relates to holders for news-
10 papers and similar articles.

One object of the invention is to provide a holder for holding newspapers such as are exposed for sale, and so designed that one or more papers may be removed without dis-
15 turbing the remainder, and without damage thereto.

A further object is to provide a very sim-
20 ple and inexpensive holder in which a bun-
dle of newspapers may be placed, and which
will not be disturbed by the wind or strong
drafts of air, or affected by the varying
numbers of papers in the holder.

Another object of the invention is to de-
25 sign a substantial and neat newspaper
holder in which any reasonable number of
papers may be inserted, and which may be
secured to the wall or placed upon a portable
or other fixed support.

The above and other objects will appear
30 as the specification progresses, reference
being had to the accompanying drawing in
which I have shown the preferred embodiment
of my invention, and in which like
reference numerals indicate like parts
35 throughout the several views thereof.

In the drawing.

Fig. 1 is an edge view of my improved
newspaper holder illustrating two sections
with newspapers in place therein.

40 Fig. 2 is a front view thereof.

Fig. 3 is a fragmentary isometric view of
the lower shelf showing it cut away to
facilitate the grasping of the paper by the
thumb and forefinger of the person remov-
45 ing a paper.

Referring now particularly to the draw-
ing, the numeral 5 indicates a support
which can be of wood or metal as desired,
laterally projecting shelves 6 are secured to
the support 5 in spaced relation, and by
means of nails or screws (not shown) and
50 on which the papers 7 are placed on edge,

these shelves preferably having a slight up-
ward pitch. The bottom shelf is cut away
as shown at 8 to facilitate and allow the
hand to easily grasp one or more papers,
and while in Figures 1 and 2 of the draw-
ings I have shown spaces for but two dif-
ferent publications, it will be obvious that
any reasonable number may be provided by
merely increasing the length of the member
5, and furnishing additional shelves.

A staple or hook 9 is secured near the top
of each individual holder or section, (one
holder comprising the space between the
shelves), and a wire 10 is secured thereto,
the upper end being bent to form a loop
11 which engages said hook or staple, the
lower end 12 of this wire being cast in-
tegral with a weight 13 which can be of
cast iron, lead or any other suitable ma-
terial, said weight having a plurality of
outwardly extending arms 14 cast integral
therewith and which terminate in loops or
eyes 15 which rest against the face of the
newspapers, holding them in upright pos-
ition in the holder, the wire 10 engaging the
upper end of the papers as shown, and it
will be obvious that the thickness of the
bundle of papers in the holder is immaterial,
75 as the hanging weight always maintains the
arms 14 in contact with the papers, due to
the fact that the said weight is pivotally
hung from the hook 9 much the same as the
pendulum of a clock, excepting that the piv-
otting point is close to the support 5.

While in the present instance I have
shown a weight provided with but three
arms, the outer eyes or loops only contact-
ing with the paper, but it will be apparent
90 that any reasonable number may be pro-
vided and that they may extend at any de-
sired angle from the weight.

From the foregoing description it will
be obvious that I have perfected a very sim-
ple and economical newspaper holder in
which papers and other articles can be
neatly arranged and held, and from which
they can be removed one by one, without
disturbing the remainder of the bundle.

100

What I claim is:—

1. A newspaper holder of the character
described, comprising a support, a shelf se-
cured thereto, the center of which is cut

away, a weight pivotally hung from the upper end of said support and outwardly projecting arms radiating from said weight.

a weight connected to the opposite end of said hanger and provided with a plurality of outwardly projecting arms terminating in loops.

2. A newspaper holder of the class described, comprising a support, a shelf secured thereto, the center of which is cut away, a hook at the upper end of the support, a bent hanger connected thereto, and

In testimony whereof I affix my signature.

GEORGE D. McINTOSH.
